(57) **CLAIM**

The ornamental design for a dual track, as shown and described.

DESCRIPTION

FIG. 1 is a top perspective view of a dual track showing our new design;

FIG. 2 is a front view thereof;

FIG. 3 is a left side view thereof;

FIG. 4 is a right side view thereof; and,

FIG. 5 is a top view thereof.

The broken lines shown in the drawings are included for the purpose of illustrating portions of the dual track that form no part of the claimed design.

1 Claim, 4 Drawing Sheets

FIG. 2

FIG. 4

FIG. 3

FIG. 5
